[57] CLAIM

The ornamental design for an front panel for an auto radio, as shown and described.

DESCRIPTION

FIG. 1 is a front elevational view of a front panel for an auto radio showing my new design;

FIG. 2 is a bottom elevational view thereof;

FIG. 3 is a rear elevational view thereof;

FIG. 4 is a right side elevational view, the left side being a mirror image thereof;

FIG. 5 is a top elevational view thereof; and,

FIG. 6 is a front elevational view thereof, shown with the instrument panel cover in an open position.

The broken line showing of radio housing is for illustrative purposes only and forms no part of the claimed design.

FIG. 1

FIG. 2

FIG. 3

FIG. 4

FIG. 5

FIG. 6
